W. J. McCloskey

ATTORNEY

UNITED STATES PATENT OFFICE.

WILBERT J. McCLOSKEY, OF TOLEDO, OHIO.

TORCH.

Application filed May 1, 1925. Serial No. 27,167.

This invention relates to jostling resistant and self-righting torches.

This invention has utility when incorporated in roadway excavation marking torches 5 as subject to disturbance by traffic.

Referring to the drawings:

Fig. 1 is a side elevation of a torch in accordance with the disclosure herein as in normal position;

10 Fig. 2 is a view of the torch of Fig. 1 as disturbed and about to swing toward self-righting or stable position of Fig. 1;

15 Fig. 3 is a view of the torch of Fig. 1, with portions broken away, the scale being enlarged;

Fig. 4 is a distributed view of the wick enveloping nipple and bushing; and

Fig. 5 is a perspective view of the loading element for the torch.

20 Reservoir member 1 is shown herein as of a base restricting form inwardly extending with annular re-entrant beading 2 as a holder for loading 3 herein shown as a cast plate within this sheet metal lower half of 25 this shell of the spherical reservoir structure of this disclosure. Opposing this semi-circular reservoir element 1 is spherical or dome member 4. These members 1, 4, are herein shown as united by a joint, seam, or 30 weld 5 in the region of the maximum diameter or bulge portion of this reservoir. The dome member 4 has central inwardly threaded throat 6 which is engaged by bushing 7 having nipple 8 therein as a guide for 35 wicking 9. Adjacent this inwardly extending threaded throat 6 is minor throat providing threaded opening 10 in which filling opening plug 11 is disposed. Upon removing the filling opening plug 11, material for combustion, as kerosene, may be introduced into 40 this reservoir or receptacle. The wicking 9 may be worked into and through the nipple 8 to leave the desired extent of the wicking 9 protrude therefrom and then through the 45 larger opening provided by this throat 6 of this sheet metal upper member 4, the loose wicking may be thrust and the bushing 7 assembled into locking position in the opening or throat 6.

50 This sheet metal unitary structure providing a vessel, is resistant against impact from horses' hoofs or vehicle wheels and when kicked, knocked, or struck will readily shift away from such source and if this be a tendency to disturb the condition of the reser-

voir as to its base, it normally is matter of but momentary disturbance, for the vessel at once is self-righting so that it will approximate the position or placing in the indicating or guarding of the excavation as in laying or repairing of tracks or pavement with flame 12 of the torch from the upper side of this vessel.

This vessel as made from sheet metal elements 1, 4, is of light weight and tough 65 throughout. The walls are stiff against battering while the loading or weight 3 in the bottom of the vessel is of a mass sufficient to load the vessel for ordinarily rocking the vessel into its upright position for normal 70 operation of the wick 9 for delivering by capillary attraction the kerosene for burning at the flame 12.

What is claimed and it is desired to secure by United States Letters Patent is:— 75

1. A torch reservoir housing comprising a dome shaped upper section, a complementary zone-shaped base section, and a load within said base section, whereby rocking of the torch is on a spherical bearing of the base 80 section continuous in spherical curvature from the lateral bounding means of the base section as enveloping the load.

2. A torch reservoir housing comprising a dome shaped upper section, a complementary 85 zone-shaped base section having an endless bead, and a rigid load element within the housing for the base section disposed inside said base section to be there retained by said bead, whereby said housing is rockably supported by said base section.

3. A torch complete in itself as to its support, said torch embodying a housing comprising a dome shaped upper portion and a complementary zone shaped base portion, 95 which portions together form a reservoir, said housing upper portion having an opening, a wick receiving bushing in said opening, and a loaded base anchored with the lower portion and disposed within the external radius of said housing, whereby rocking of the torch toward righting position is on a continuous spherical bearing from a tilted supporting side of said housing to a position of rest with its loaded base downward and the wick bushing upward with the housing portion thereabout convex downward. 105

In witness whereof I affix my signature.
WILBERT J. McCLOSKEY.
